GAME BOARD

Jack Skoler, 51-15 Van Kleeck St.,
Elmhurst, N.Y. 11373

Filed Apr. 29, 1975, Ser. No. 572,927

Term of patent 14 years

Int. Cl. D21—01

U.S. Cl. D34—5 SS

FIG. 1

FIG. 3

FIG. 2

FIG. 1 is a plan view of a game board showing my new design;

FIG. 2 is a reduced front view in elevation thereof, side and rear views being similar; and

FIG. 3 is a reduced underside plan view of the design.

I claim:

The ornamental design for a game board, substantially as shown and described.
